UNITED STATES PATENT OFFICE.

FLORENCE CRANE GROVER, OF HOLLYWOOD, CALIFORNIA.

KITCHEN-SINK WATER-STOP PLUG.

Application filed March 29, 1922. Serial No. 547,650.

To all whom it may concern:

Be it known that I, FLORENCE CRANE GROVER, a citizen of the United States, and a resident of Hollywood, in the county of Los Angeles, State of California, have invented a new and useful Improvement in Kitchen-Sink Water-Stop Plugs, of which the following is a specification.

This invention relates to a simple, economical plug to be inserted in the ordinary drain-pipe say in a kitchen sink to close the same effectually.

One of the objects of this invention is to provide such a plug of simple construction which may be used in any ordinary drain-pipe without requiring any special construction of drain-pipe or sink to receive it.

Other objects will appear from the following more detailed description, in which the drawing represents by way of illustration, in Figure 1, a section taken through the stop plug; Figure 2, a plan view of the plug; and Figure 3, a section of the device in place in a kitchen sink.

Referring briefly to the prior art, it has been quite common to make sink stop plugs of various kinds, but primarily they have consisted of a thick disc of rubber carrying a ring and usually an unsightly, unsanitary chain; or else a metal or other plug constructed to coat with a specially designed sink, or drain-pipe.

By my invention, I avoid both the difficulties, and expense of these prior constructions. In the detailed description of my invention, which I give below, it is to be understood that many changes may be made by those skilled in the art, and yet the spirit and function of my device will remain the same.

In constructing my device, I take a disc of metal 2, preferably brass which may or may not be nickel-plated or otherwise artistically finished. The diameter of the disc may vary, but 3 inches has been found to be a serviceable size, made from stock about one-sixteenth of an inch in thickness, although the thickness of this material is optional. This disc is preferably given a

slightly concave flexure as shown in Figure 50 1, for purposes more particularly set forth below.

A disc approximately the same diameter is now provided from a water-impervious material such as cork, leather, rubber, etc., 55 the cork serving in the present instance admirably. This disc of material is also made preferably from relatively thin material, say about one-eighth of an inch thick, since it is one of the important contributions of my invention, that thin material can be used in making these stops. Such material need not be more than $\frac{1}{4}$ inch thick for example, but is preferably thinner as indicated. The two discs are now assembled. For this purpose a staple made of more or less heavy, spring wire is preferable, as illustrated in the drawing. The shank of the staple has a notch 5 and a co-acting shoulder 6. This staple is inserted 60 through perforations in the two discs, and it is also desirable but not absolutely necessary to solder the staple to the metal disc 65 rigidly. It is also likewise desirable to attach the two discs together rigidly as by screws, 70 rivets, etc., 1, 1 shown in the drawing. The upper part of the staple, 4, forms a handle by means of which the stop may be removed or placed in position, or to which a chain 75 may be attached.

This stop is particularly useful in connection with the ordinary perforated cap closure used on the drain-pipes of sinks, etc. The stop is held by the handle, 4, and the ends 7, of the spring wire staple are forced 85 through perforations of the cap closure. By forcing the stop down until the notch 5, rests in a perforation, the flexure of the metal disc forces the water-impervious material against the floor of the sink, simply 90 and effectually closing the drain-pipe outlet. It is to be noted that by the disclosed means, a thin disc of water-impervious material may be used because the strain of placing and removing the device is carried 95 wholly by the metal.

Having now disclosed the best means of carrying out my invention, it being under-

stood that obvious changes in construction and substitution of materials may be made therein by those skilled in the art, I claim—

A plug stop comprising a metal disc and 5 a second disc of cork secured together by means of a staple, the metal disc being flexed concavely, the shank of the staple being formed to act as a securing means to lock the

plug stop in position over an outlet to be closed, whereby the second disc is wedged 10 against the floor of the sink, the diameters of the discs being substantially equal to each other and greater than the diameter of the outlet to be closed.

FLORENCE CRANE GROVER.
